(57) **CLAIM**

The ornamental design for a bed for magnetic resonance tomography diagnosis apparatus, as shown and described.

DESCRIPTION

FIG. 1 is a front perspective view of a bed for magnetic resonance tomography diagnosis apparatus showing our new design;

FIG. 2 is a front elevational view thereof;

FIG. 3 is a rear elevational view thereof;

FIG. 4 is a top plan view thereof;

FIG. 5 is a bottom plan view thereof;

FIG. 6 is a left side elevational view thereof;

FIG. 7 is a right side elevational view thereof;

FIG. 8 is a sectional view taken along line 8-8 as shown in FIG. 2 thereof; and,

FIG. 9 is a sectional view taken along line 9-9 as shown in FIG. 4 thereof.

The broken lines illustrate portions of the bed for magnetic resonance tomography diagnosis that form no part of the claimed design.
